RESISTANCE GRID

Marvin A. Du Bois, Chicago, Ill., assignor, by
mesne assignments, to The Post Glover Elec-
tric Company, Cincinnati, Ohio, a corporation
of Ohio

Application December 2, 1935, Serial No. 52,531

6 Claims. (Cl. 201—69)

The present invention relates to electrical resistance grids and electrical resistances containing the same and has for an object the provision of a novel and relatively inexpensive grid element and, as a further object, the provision of an effectively ventilated, long lived and compact electrical resistance for use in various installations.

A further object of the invention is to provide a novel method of forming highly efficient resistance grids of sheet metal with a minimum of loss of sheet stock in scrap or waste.

Another object is to provide a stamped sheet metal resistance grid characterized in that each grid, between the terminals thereof, is constituted by a continuous series of angularly related sections so disposed with relation to each other as to provide for the closer disposition of the sections thereof nearest the edges of the grid, and for the wider spacing of certain non-adjacent sections providing for the more ready dissipation of heat from the more closely spaced sections to the edges of the grid, the said relation of these continuous sections further permitting of the stamping of successive grids from a ribbon or elongated sheet of electrical steel in a fashion productive of a minimum of waste of the sheet stock from which the grids are stamped.

Another object of the invention is to provide a resistance grid of stamped sheet electrical steel that is designed to provide a high continuous carrying capacity factor in proportion to the resistance thereof and which in use in a resistance device will readily combine the desirable factors of very nearly uniform temperature distribution throughout the major portion of each grid with a surprisingly low temperature at the terminals thus avoiding the destructive action of heat on the insulating supports therefor and upon the insulation and other parts of the actuators and lead wires associated with the terminals.

Another object of the invention is to provide sheet metal resistance grids of relatively thin gauge and electrical resistance devices comprising the same wherein the grids may be very closely spaced without danger of warping and thus minimizing overheating, or burning out of the grids.

Another object is to provide electrical resistance devices comprising grids of the aforesated characteristics that require a minimum of supporting material and which are easily and rapidly assembled and which, in general, provide an ideally efficient resistance device of compact form,

light weight, and designed to have a high degree of practically uniform self-ventilation.

A further object is to provide resistance devices of the character described wherein the grid elements of a given gauge of sheet stock and at a predetermined spacing have a higher continuous carrying capacity than heretofore known grids of similar thickness and width and like spacing that have equal individual resistance.

Another object is a simple and inexpensively practiced method of cutting grids of the invention from an elongated steel sheet.

These and other objects are attained by the method and means herein described and disclosed in the accompanying drawings, in which:

Fig. 1 is a plan view showing in full lines the resistance grid in relation to the sheet in which it is cut, and in dotted lines, the position of the die to cut a succeeding grid.

Fig. 2 is a cross sectional view of a resistance device embodying the grid of the invention.

Fig. 3 is a view taken on line 3—3 of Fig. 2.

Fig. 4 is a cross sectional view of a resistance device showing a modified form of mounting the grids and of providing additional support therefor as may be required in rare instances of excessively close spacing and very thin grids.

Fig. 5 is a fragmental schematic view showing a modified form of the mounting of the grids of the invention in multiple banks.

Fig. 6 is an enlarged view taken on line 6—6 of Fig. 5.

In the art of constructing resistors, practice has been largely with cast metal grid resistors or the so called ribbon resistors, and although the use of sheet metal is not unknown, previous attempts to use it have resulted in products inferior to the present device and incurring large waste of material. The present invention provides a new sheet metal grid which has advantages over the cast grid resistors in that it gives a more even distribution of heat on the grid and is cool on the ends of the grid during use, allowing the support to remain cool and thus retarding the carbonization of the mica tubing. Furthermore, the connecting terminals will therefore remain cool and the possibility of destroying insulation on wires connected to the terminals is reduced. The devices made in accordance with the present invention also have specific advantages over cast grid resistors in that they are non-breakable and will withstand high overloads without warping or drooping of the grids whereas many cast-grid resistor grids droop when hot so that the loops of the grids will touch each other.

In addition to this the resistance banks of the present invention will require a lesser amount of space than required for a cast grid resistor of equal resistance and carrying capacity because of the thin cross section of the grid which allows a higher ratio of air space to space taken up by grids. In addition to this the entire structure is lighter in weight for equal carrying capacity and resistance. Furthermore, the present device offers a lower thermal coefficient of resistance. The device furthermore has advantages over ribbon type resistors in that no porcelain need be used so that the resistor may be heated and drenched with water without danger of damage. Furthermore, the number of supporting bolts is less and of those used a portion can be arranged for floating mounting so as to allow for expansion. The type of terminal necessary may be such as can be firmly attached but easily moved when desired.

The individual grid of the invention indicated generally by the reference numeral 10 is an integral stamping from suitable electrical sheet steel having a pair of end lugs 11 with perforations 12 therein connected by a flat strip forming a circuitous path and comprising a succession of oppositely extending open ended loops connected in a series between said lugs. The shape of the loops is such that a pair of closely spaced sections 13 which are of uniform cross section and size and having a narrow space 14 between, are connected together at a common end 15 and each of these sections 13 in turn connects at its remaining end with an angularly divergent portion 16. The portions 16 in turn connect the sections 13 of the next adjacent oppositely extending loops or with the perforate end lugs 11. Thus it will be noted that the narrow opening 14 between the sections 13 of each loop communicates with a wider opening 17 which is bounded by sections 13 on adjacent oppositely extending loops and the intervening portions 16. It will further be noted from a further inspection of Fig. 1 that each of the larger openings 17 is occasioned by the cutting out of the loops of a preceding or succeeding grid. Hence, the amount of scrap or waste stock occasioned by the production of these grids according to the present invention is very small, and in practice represents a seventy-five per cent saving of scrap metal over heretofore known methods of forming stamped sheet metal resistance grids. This factor of saving is deemed important because the nature of electrical sheet steel is such as to render the value of its scrap very low as compared with its initial cost because this type of metal does not have a wide field of utility for other purposes. Furthermore, a greater number of grids can be stamped from a given piece of metal than by heretofore known methods.

The method of forming these grids consists in feeding a steel sheet or strip 18 endwise beneath a punch and die, the sheet 18 in Fig. 1 being indicated in full lines and exclusive of the completed grid shown in position prior to the next operation of the die, the position of which is shown in dotted lines. Thus a complete grid is struck from the sheet at each operation of the die and the outline of half of the succeeding grid is cut from the sheet in the same operation. This affords a very rapid and inexpensive fabrication of the metal into grids with a minimum of scrap which will be readily apparent from an inspection of Fig. 1. The method of forming the grids may be stated to be constituted by the steps of successively stamping out the point shaped open-

ings 17 and the irregular openings 19. With each stroke leaving the forward profile of the grid with tongues shaped like opening 14 on the sheet and, on the next succeeding operation of the die, cutting a similar outline which severs the said 5 tongues.

The shape of the grid thus formed is, as before indicated, not only productive of a maximum number of grids with a minimum amount of waste from a given quantity of sheet material, but it 10 also affords the utilitarian features of a substantially even distribution of the heat over the major area of the grid and a comparatively low temperature at the terminal lugs thereof. It will be further noted that there is for all practical purposes 15 uniformity of cross section of resistance metal in the circuitously shaped strip between the end lugs. The relatively close proximity of the sections 13 of a given loop is compensated by the fact that around all sides and ends of the said sections 13 20 there is an enlarged ventilating area communicating with the outside atmosphere and tending to effect relatively uniform distribution and dissipation of heat. It has been found that in use this uniform heating and efficient ventilation precludes warping of the grids when carrying rated current and that when the current is increased to bring the grids to a white heat, there is but a slight amount of warping which is not sufficient to cause even the more closely spaced grids to 25 touch at any point. Furthermore, when the grids are allowed to cool, they return to practically original position. The warping just referred to obtained only under extreme conditions and under conditions wherein both of the lugs 11 30 were rigidly fixed. As will be hereinafter described in greater detail, it is possible to eliminate observable warping by mounting the lugs of a bank of grids on a fixed through bolt at one end and on a floating through bolt at the other end 40 so that when the grids are excessively overheated, e. g., to a white heat, the grids are allowed to expand so that the distance between the fixed and floating bolts would increase slightly but sufficiently to accommodate the elongation due to 45 expansion.

The grids of the invention adapt themselves to the mounting in banks as illustrated in Fig. 2 or in a connected series of banks as suggested in Fig. 5. They are further adapted to mounting in 50 double banks as suggested in Fig. 4 and in the latter embodiment when the grid thickness is #18 gauge or thinner and the grid spacings are very small, it has been found desirable to use the center bolts and spacers illustrated in Fig. 4 in 55 order to preclude warping and possible touching of the rigidly secured grids under continued overload heating. The device of Fig. 2 may have a center bolt and spacers applied thereto if the grids are thin and are closely spaced.

It is well understood in the art that resistors of various types, for example, such as illustrated herein, are adapted for use upon electric locomotives such as mine locomotives, in mills, and in various environments, and that in the design 65 and construction of the various devices and apparatus employing these various resistors, it frequently happens that the design or lay out has been made with compactness as an important object and that no particular provision has been 70 made for the exact location of the necessary resistors. For all such conditions, it is particularly desirable and useful to have a fully efficient resistor as small and compact as possible so as to permit the installation of the resistors if need 75

be in restricted remaining space or spaces. In the following detailed description, the resistors will be considered only from the viewpoint of the necessary end supports for the through bolts which carry the grids and these latter elements.

Referring now to Figs. 2 and 3 a resistor of the present invention employing the grids herefore described comprises essentially suitable end supports or frames 20 and 21. One of these end frames such as 20 has a pair of elongated supporting bolts 22 inserted through it and upon these bolts are mounted insulating tubes 23 of mica or the like. A suitable number of insulating washers or spacing collars 24 are then placed over the tube and in abutment with the inner face of wall 20 to establish the spacing between said wall and the first grid 10, a terminal lug 25 which may constitute a mere perforated conductor plate contacting the first grid and suitably arranged for connection with a terminal 26 of a lead wire 27 being mounted in position at this point. Thereafter, successive washers or groups of washers or spacing collars 24 of metal and of insulation are added to the stack 25 and the additional grids 10 mounted as shown by passing the insulated supporting rods through the perforations in the terminal lugs 11 of the grids to attain the requisite spacing and the electrical connection between grids as is well known 30 in this art. The necessary additional terminal lugs are placed at desired intervals to secure the desired different resistances for the several taps and the entire stack is finally bound as a rigid unit in this case by drawing the remaining end 35 frame 21 tightly upon the stack by means of nuts 28 on the threaded ends of the bolts. This particular form of mounting may be used when the grids are stamped from relatively heavy gauge sheet metal, e. g., thicker than #18 gauge, and 40 with relatively wide spacing. A structure so arranged may, when overloaded to a degree that brings the grids to a white heat, show some slight warping of the grids while at that heat but this has been found insufficient to cause the grids 45 to touch and short circuit and it has been found furthermore that upon cooling, the grids will return to substantially their original shape. It can be readily appreciated that the cost of resistors of this type is relatively low and that comparatively little skill is required in the assembly 50 thereof.

It is preferred in general and not only for resistors employing very thin gauge grids, e. g., from #18 gauge to #26 gauge, to rigidly fix one 55 of the bolts 22 in the end frames as specifically illustrated in Fig. 3 and to provide a floating mounting of the remaining bolt in the end frames as detailed in Fig. 6. This construction is provided by forming an elongated slot 29 in 60 each end frame in lieu of a perforation which snugly receives the bolt and providing means whereby the stack is rigidly clamped together with the bolt 22 and a means such as a collar 30 and shoulder-forming washers 31 which permits the rigidly clamped bolt and grid assembly to move longitudinally relative to the frame when the grids elongate slightly due to high heating. In ordinary construction the heating of a grid to a white heat will increase the distance between 65 the rigidly anchored bolt and the floating bolt support sufficiently to take care of expansion. Any other suitable mode of providing for the free floating of one of the support bolts may be employed in lieu of the means just illustrated 70 and described.

It will have been noted from the foregoing that the shape of the stamped grids of electrical sheet metal has been designed to afford a relatively uniform heating of the grids throughout the area thereof so that by the use of floating bolt supports it is possible to simply and inexpensively construct resistors with only two supports for the bank in cases where the grid spacing is three-eighths of an inch (3/8") or more and the gauge of the grids is of #18 or thicker. When it is desired to use closer spacings and thinner grids than the foregoing, it is possible to use a center bolt with spacer washers entered through one of the spaces 17 between the loops of the grid. This would be provided essentially as a matter of 15 safety against extreme and continued overheating due to difficulties in the electrical system or the load. The use of additional supports intermediate the ends of the grids and the necessary spacing washers effects some restriction of the 20 escape of heat although not to the degree encountered in resistors now on the market and in which a multiplicity of supports are utilized.

As shown in Fig. 4 it is possible to assemble resistors employing double interleaved banks of 25 grids wherein the composite bank will have the same resistance per unit of length as a single bank of similar grids at half the spacing of either the top or bottom section. Under some conditions such a double bank may be found 30 advantageous even though, by reason of the fact that the air temperature will reach its permitted maximum before the grids have reached their maximum permitted temperature, the carrying capacity value is somewhat reduced. This is 35 apparently due to the restriction of air flow caused by the use of additional center supports 220. As shown somewhat diagrammatically in Fig. 5 a plurality of banks may be arranged by suspending the first bank of grids from a rigidly 40 mounted bolt 22 fixed between the elongated end frames 33, which frames are provided with elongated slots 34 at necessary intervals to receive the remaining bolts 22. In such installation the intermediate bolts 22 would have adjacent sides 45 of adjacent grid banks mounted thereon so that the entire assembly is suspended from the uppermost rigidly mounted support. One or more of these elongated banks may be of course adaptable to assemblies which will fit compactly into 50 long narrow confined spaces but nevertheless with very effective operation.

What is claimed is:

1. As a new article of manufacture a resistance grid comprising an integral sheet stamping 55 having a pair of mounting lugs connected by an intermediate uniform strip forming a circuitous resistance path, said strip comprising a succession of parallel legged loops alternately extending in opposite directions from the longitudinal axis of the grid, the loops on each side of said axis being spaced apart by an opening greater than the combined width of the parallel legs of the intermediate loop on the opposite side of said axis, each leg of each loop being offset laterally from every other leg of the remaining loops, and each of said legs being longitudinally aligned with one of said openings.

2. A new article of manufacture a resistance grid comprising an integral sheet stamping 70 having a pair of mounting lugs connected by an intermediate uniform strip forming a circuitous resistance path, said strip comprising a succession of parallel sided loops alternately extending in opposite directions from the longitudinal axis 75

- of the grid, the loops on each side of said axis being spaced apart by an opening shaped like the reversed counterpart of one of said loops, the interior openings of the several loops on one side
- 5 of the longitudinal center of the grid forming a continuation of the loop-spacing openings on the other side, the mounting lugs being disposed beyond the extreme loops of said grid.
3. A resistance grid of stamped sheet electrical resistance material and comprising a pair of end mounting lugs connected by an intermediate succession of oppositely extending loops, integral portions disposed angularly to the adjacent legs of successive loops and connecting said adjacent legs whereby said legs are offset from one another in staggered parallel relation and form, between alternate loops, enlarged ventilating openings.
4. A resistor comprising spaced end frames having aligned perforations therein at one side and aligned elongated slots in the other side, a pair of suitable support bolts extending respectively through the said pair of perforations and the said pair of slots, a suitably spaced stack of stamped sheet metal grids having perforate lugs at opposite ends receiving the support bolts, said grids each having oppositely extending open loops in staggered relation on opposite sides of the longitudinal axis of the grid and enlarged ventilating spaces on each side of each loop, means rigidly securing together the perforate lugs on one end of said stack, end frames and the supporting bolts in said perforations of the end frames and means rigidly securing the lugs on the remaining end of the stack on the remaining bolt, said bolt being adapted for movement in the slots in said end frames and permitting expansion of the grids.
5. As a new article of manufacture a resistance grid of stamped sheet material comprising a pair of end lugs and a connected series of spaced loops disposed on opposite sides of the longitudinal axis of the grid in staggered relation whereby enlarged openings are provided between adjacent loops on a common side of said axis, said enlarged openings communicating with smaller interior openings of intermediate loops on the opposite side of said axis and providing, upon electrical energization of the grid, increased heat dissipation resulting in uniform heating of all of said loops.
6. A resistor comprising spaced end frames each having aligned pairs of elongated slots, support bolts each having opposite ends extending into slots in opposed end frames, a suitably spaced stack of stamped sheet metal grids having perforate lugs at opposite ends receiving the support bolts, said grids having oppositely extending open loops in staggered relation on opposite sides of the longitudinal axis of the grid and enlarged ventilating spaces on each side of each loop, means rigidly securing the grids to the bolts and means retaining the bolts against accidental separation from the end frames, said bolts being adapted for movement in the slots in said end frames and permitting expansion of the grids.
